UNITED STATES PATENT OFFICE.

WILLIAM S. WESTON, OF CHICAGO, ILLINOIS

CASTING APPARATUS.

No. 900,807.

Specification of Letters Patent.

Patented Oct. 13, 1908.

Application filed March 8, 1907. Serial No. 361,236.

To all whom it may concern:

Be it known that I, WILLIAM S. WESTON, a citizen of the United States, and a resident of Chicago, county of Cook, and State of Illinois, have invented certain new and useful Improvements in Casting Apparatus, of which the following is a specification.

The invention relates to improvements in casting apparatus in which a number of permanent molds are constructed and arranged to move in endless series so as to be filled from a continuous stream of molten metal at one part of the apparatus and to discharge the cast articles at another part.

The primary objects of my invention are to provide an arrangement of the molds on a traveling and preferably rotating carrier, together with improved means for automatically opening and closing the molds and discharging the castings; to provide an improved arrangement whereby the closing of the molds operates to form an uninterrupted trough along which the molten metal may run from mold to mold while the latter are filling; to provide improvements in the construction of the working faces of the mold and to provide improved automatic means for securing inserts and the like in the mold cavity.

The invention consists in the features or construction, combinations and arrangements of parts hereinafter set forth, illustrated in the accompanying drawings and more particularly pointed out in the appended claims.

In the drawings, Figure 1 is a plan view of a segment of my machine. Fig. 2 is a vertical section on line 2—2 of Figs. 1 and 10, showing the mold in closed position. Fig. 2^a is a detail vertical section of parts shown in Fig. 2, but in a slightly different plane. Fig. 3 is a detail section on line 3—3 of Fig. 10, showing the mold in open position and partially rotated or inverted to discharge the casting. Fig. 4 is a similar view taken in section on the line 4—4 of Fig. 10, showing the mold sections in partially closed position and ready to receive inserts or the like. Fig. 5 is an exterior elevation of a pair of closed mold sections. Fig. 6 is an elevation of one of the inner mold sections showing its working face. Fig. 7 is an elevation of the outer mold section looking at its working face. Fig. 8 is a horizontal cross section through a pair of closed mold sections taken on the line 8—8 of Figs. 2 and 5. Fig. 9 is a partial hori-

zontal section of one of the outer mold sections taken on the line 9—9 of Fig. 5. Fig. 10 is a plan view on a small scale of the entire machine, with a portion of the molds removed. Fig. 11 is a cross section on the line 11—11 of Fig. 10 with two of the molds shown in elevation.

A series of traveling molds are mounted upon a suitable carrier or wheel frame that is preferably built up of structural steel. In the form shown, the carrier or wheel frame comprises a central hub 1 journaled upon a short upright spindle or shaft 2, a series of radial frames comprising upper and lower angle bars 3 connected by brace bars 4. To the ends of the radial members or spokes of the wheel frame, are secured upper and lower circular angle bars 5. The spindle 2 is mounted upon a pedestal 6 so that the wheel frame may rotate in an approximately horizontal plane. A row of anti-friction balls 7 (see Fig. 2) are interposed between suitable bearing members 8 and 9 secured to the hub 1 of the wheel frame and to the upper end of the pedestal 6.

Rotation is imparted to the wheel frame or mold carrier, preferably by means of an annular rack 10 secured to the lower radial angle bars 3 and a pinion 11 mounted upon a vertical drive shaft 12 and meshing with the teeth of the rack 10. The drive shaft 12 is mounted upon a suitable bearing 13 carried by the pedestal 6 and may be driven by any suitable application of power.

The series of two-part molds, each comprising a section 14 and a section 15 are carried upon the periphery of the wheel frame or mold carrier, and preferably between a series of supports or plates 16 secured in radial position to the upper and lower rims or circular angle bars 5 of the wheel frame or mold carrier.

For convenience in making repairs and the like, each mold is preferably mounted upon the wheel frame or carrier independent of the other molds and in such manner that it may readily be moved. For this purpose, the outer, or what may be termed the movable section 15 of each mold, is carried upon the inner mold section, as hereinafter described, and the latter is removably fitted between two of the adjacent radial supports or plates 16. For this purpose, the supports 16 are T-shaped at their inner edges or provided with lateral, vertically disposed flanges 17, and these supports or plates are also pro-

vided on opposite sides near their inner edges, with vertical ribs 18, all as clearly shown in Fig. 1. The inner or fixed section 14 of each mold (see Fig. 8) is shaped to fit 5 snugly between two adjacent radial supporting plates, its inner face abuts against the flanges 17 or T-shaped edges of the plates and the sides of the mold section 14 are provided with vertical grooves engaging the 10 ribs 18. The outer mold sections 15 are also shaped to fit snugly between the radial plates or supports 16 in closed position and the upper portions of both the inner and outer mold sections are enlarged laterally 15 so as to extend over the upper edges of the supports or plates 16 to the central radial line of the supports, as further shown in Fig. 1. In this way the upper portions of the inner mold sections 14 abut one against the 20 other and the upper portions of the outer mold sections 15 abut in a similar manner when in closed position. The upper portion of the inner mold sections 14 are also off-set so as to overlap the outer edge of the wheel 25 frame, as indicated in Fig. 2. In this manner, the molds are rigidly and securely held in position upon the carrier but may be readily slid in vertical direction to position on the carrier or as readily removed there- 30 from for repairs, renewals and the like.

Each of the inner mold sections 14 is provided at its lower end with a downwardly and outwardly projecting part 19 which carries the swinging support for the outer 35 mold section. This swinging support or lever 20 is preferably formed of two members which extend on opposite sides of the projection 19 and are connected thereto by a transverse pivot bolt 21. The upper ends of 40 the members of the swinging support or lever 20 extend outside of a pair of rearwardly projecting lugs 22 (see Figs. 5 and 8) and are pivotally connected thereto by a transverse bolt 23. The lower ends of the 45 members of the swinging support or lever 20 are secured to a counter-weight 24 which tends to hold the movable mold section 15 in closed position. The movement of the supports or levers 20 for opening and 50 closing the molds is controlled preferably by means of a cam track 25 carried on a series of pedestals 26 (see Figs. 2, 3, 4 and 11) and which engages a series of rollers 27 on the swinging supports or levers 20. 55 Each lever 20 is provided with a roller 27 suitably journaled upon a block or mount 28 secured between the members of the swinging lever (see Figs. 2 and 5). The movement of the mold section 15 is also con- 60 trolled by a bent link or swinging support 29, the inner forked end of which is pivoted to a stud 30 screw threaded into the lower end of the inner or fixed mold section 14. The outer or upper end of the link 29 at the outer 65 end is flattened and extends between the

lugs 22 on the outer mold section and is pivotally connected thereto by a cross pin or bolt 31. By reference to Figs. 2, 3, 4 and 11, it will be observed that the shift of the supporting lever 20 upon its pivot 21 moves the 70 mold section 15 to and from the mold section 14 to open and close the mold while the link or swinging support 29 operates to partially rotate the mold section 15 upon the pin 23 so that the mold section may be inverted 75 (shown in Fig. 3) to discharge the casting and so that the mold section is also brought back accurately to position to close the mold, as shown in Fig. 2. In addition to the cam track 25, a second cam track 32 is also preferably provided upon the uprights or supports 26 that is arranged to engage a series of rollers 33, one of which is journaled between a pair of lugs 34 projecting laterally from the upper portion of each outer mold 85 section 15.

In one complete revolution of the machine, the outer mold section 15 of each mold is opened and closed changing from the position shown in Fig. 2 to that shown in Fig. 3, 90 then back to the position shown in Fig. 4 and finally back again to the closed position shown in Fig. 2. This movement is effected by the stationary cam tracks 25 and 32 which are bent and twisted so that their 95 working faces are arranged in different planes, to form proper tread surfaces for the rollers 27 and 33 on the swinging supports 20 and on the movable mold sections 15. That is to say, the surfaces of the cam tracks are in 100 all positions parallel with the axis and peripheral surfaces of the rollers. A single cam track for shifting the swinging supports 20 might be sufficient, but as stated a second cam track 32 is preferably provided for assisting in the controlling movement of the outer or movable mold sections 15 upon the pivot pin 23. With the arrangement shown, the cam track 32 operates to close the mold while the cam track 25 operates to open the 110 same so that by using two cam tracks, the outer mold sections 15 are positively shifted in opposite directions and to open and closed positions. The outer section of each mold is opened to its full extent at the point indicated by the line 3—3 in Fig. 10 and at this time the mold section is in the position shown in Fig. 3. As the machine is rotated in the direction of the arrow shown in Fig. 10, the cam track 32 is brought to bear upon the 115 roller 33 of the outer mold section 15 and shifts the mold section first to the position shown in Fig. 4 and finally at a point indicated by the line 2—2 in Fig. 10, the outer mold section is brought fully to its closed position which is shown in Fig. 2. The mold sections remain closed during a portion of the revolution of the machine (in the form shown the molds are held closed through slightly over a quarter of a revolution) and when the 120 125 130

mold is so closed the cam track 25 is out of contact with the roller 27 on the swinging support or lever 20 (see Fig. 2). When the mold reaches the point where it is opened by 5 the movement of the machine, the cam track 25 is brought to bear against the roller 27 on the swinging support or lever 20 and then gradually shifts the movable mold sections to the position shown in Fig. 3 and at line 10 3—3 in Fig. 10. During the opening of the mold section, the upper track 32 is gradually bent away into the shape indicated in Fig. 10.

The cam track 32 might be depended on to hold the mold sections 15 in closed position, 15 but preferably other additional means are provided to positively hold the mold sections in closed position. For this purpose, a series of flat springs 35 (see Figs. 2 and 11) are secured to the upper edges of the radial supports or plates 16 and these springs are provided in their outer ends with shoulders or offsets 36. As the mold sections 15 are swung to closed position the laterally offset upper portions thereof pass over the spring 20 catches or latches 35 until the shoulders 36 on the spring latches engage the outer faces of the mold sections, as shown in Fig. 2, at the right hand side of Fig. 11 and in Fig. 5, to hold the mold sections together. As stated, 25 the cam track 25 in the closed position of the molds, is not in engagement with the rollers 27 on the swinging supports or levers 20, so that the counter-weight on the latter may freely exert its pressure to assist in holding 30 the molds in closed position and to insure that the bottoms of the mold sections will be snugly held in engagement. A pair of set screws 37 are provided on the outer face of each mold section 15 near its lower edge (see 35 Figs. 2 and 5) and against which the members of the swinging support 20 bear when in closed position to force the bottom parts of the mold in closed contact.

When the mold reaches a point *a* in Fig. 10, 40 it is necessary to release the latch 35 and for this purpose a lug or strap 38 is secured to the under side of the cam track 32 at this point. At the position *a* (see Fig. 10) the cam track 32 begins to curve away from the machine 45 (see dotted lines in Fig. 2) so that the lug 38 is in position to depress the spring catches 35 and release the mold sections 15. At the same time the cam track 25 (see dotted lines in Fig. 2) is brought against the rollers 27 on 50 the shift lever 20 and starts to open the mold. The mold sections are thus not only automatically opened and closed, but the movable mold section is also inverted, as shown in Fig. 3, to discharge the casting. The sections of each mold and the operating supports therefor, are connected together as a unit and are separately and independently arranged in the machine so that the molds may be readily removed for repairs, renewals or the like without 55 interrupting the operation of the machine.

While the improved machine may be adapted to manufacture a variety of cast metal articles, the molds illustrated in the drawings are designed for the manufacture of railway brake shoes, and particularly that class of shoes provided with preformed retaining lugs and inserts of wrought iron or steel, and some of the features of the invention relate to means for holding the lug and the steel or iron insert or back in position in the mold 70 during the casting operation.

In Fig. 3 the brake shoe is shown as just discharged from the mold and the retaining lug and back reinforcement of wrought iron or steel are shown, the latter by dotted lines. 80 The lug and back are shown in full lines and held in position in the mold in Figs. 2 and 4.

The device for holding the lug and reinforcement or insert preferably comprises a pair of jaws 39 arranged within a cavity 40 in 85 the back of the mold section 15 between the lugs 22 thereon. These jaws are pivotally mounted upon the cross bolt 23 and are provided at their ends with fingers or teeth 41 and 42 which engage the opening in the retaining lug of the insert. The jaws are provided with outwardly extending arms 43 which are arranged on each side of the flattened head or end of the link 29 and are provided with elongated slots 44 engaging eccentric lugs 45 fixed to the head or end of the link 29. The shift of the link 29 and of the eccentric 45 fixed thereto relatively to the arms 43 of the jaws as the mold section 15 moves from the position shown in Fig. 2 to 90 that shown in Fig. 3, moves the jaws from the closed position shown in Fig. 2 to the open position shown in Fig. 3, while the reverse movement of the mold section 15 and the link 29 serves to bring the jaws back to 100 the closed position. In the closed position of the jaws 39 the fingers 41 thereof extend into the eyelet or opening of the retaining lug while the fingers or teeth 42 close together 105 back of the retaining lug and serve to close up the opening through the lining of the mold, as hereinafter described. In the position shown in Fig. 4, the mold section 15 and the jaws 39 have shifted toward the closed position but the jaws are still sufficiently 110 open to permit the placing of the retaining lug, and wrought metal back in position.

The adjacent parts of the upper portions of the mold sections 14 and 15 are cut away to form a pouring trough or groove 46 extending 115 along or parallel to the parting lines of the mold sections when the latter are in closed position. One wall of the trough is formed on the fixed mold sections 14 and the other on the movable mold sections 15 and since, as 120 stated, the upper portions of the mold sections are in contact when in closed position, the trough extends continuously across all of the closed molds. The sections are preferably formed of cast iron and those portions of 125 130

their surface which form the trough 46 are preferably provided with a lining 47 of refractory material held in place by wrought metal plates 48 detachably secured to the mold sections by screws or the like, as indicated in Fig. 1. Extending from the bottom of the trough 46 and in the parting line between the sections, are gates 49 which lead to the mold cavities. The portion of the machine at the right hand side of Fig. 10 is slightly elevated so that when the metal is poured into the trough at a point *b*, it will tend to flow through the trough in a direction opposite to the movement of the machine. The trough serves to guide the molten metal from mold to mold so that two or more of the molds, depending upon the amount of elevation of the machine, may be filling at the same time.

Referring to Fig. 10, the operation of the machine may be briefly described as follows: The machine and the series of molds are moved continuously in the direction indicated by the arrow. When the mold sections arrive at the point 4-4, the inserts are put in place, as shown in Fig. 4. The mold sections are then gradually brought to the closed position shown in Fig. 2. As the molds approach and pass the point *b*, they are filled with molten metal from a suitable spout or ladle, all surplus metal after each mold is filled flowing on through the trough 46 which extends continuously over all of the closed molds into the next succeeding molds.

By the time the molds reach the point *a* the castings are set and the molds are open to discharge the finished castings at the point 3-3. The molds then pass on to the point 4-4 where they are again provided with inserts and lugs for the next series of castings.

The bodies of each of the mold sections 14 and 15 are made of cast iron. The working faces, that is the surfaces exposed to the action of the molten metal may be formed in the cast iron body. Preferably however, the mold cavity is provided with a lining of wrought iron or steel or an alloy of iron that has a considerably higher fusion point than the cast iron of the body of the mold section.

If the mold cavity were formed in the cast iron body of the sections, the labor incidental to planing and fitting of the sections would have to be repeated each time the mold was discarded because burned or otherwise damaged, whereas a renewable lining of sheet iron or steel may be formed at small cost.

As stated the particular molds illustrated are designed for the manufacture of brake shoes and, as shown in Figs. 2, 7, 8 and 9, the outer mold section 15 which forms the back of the brake shoe, is provided with a lining 50 of substantially uniform thickness. This lining may be constructed at relatively small expense by shaping a suitable sheet iron or steel blank under a press. It is attached to

the main body of the mold section 15 by screws 51, as shown in Fig. 7, and may thus be readily renewed at small cost when burned. The offset portion 52 of the lining in which the retaining lug of the brake shoe is placed, projects through an opening 53 in the mold section 15 and into the cut away space or recess 40 where the jaws 39 are located. To allow the ends of the jaws to enter and engage the lug the portion 52 of the lining is provided with a slot 54 (see Fig. 9) that is of a width equal to the thickness of the jaws 39. This slot or opening 54 in the surface of the mold is closed up by the wrought iron lug of the insert projecting therethrough and by the engagement of the teeth 42 of the jaws 39, as shown in Fig. 2, so that none of the molten metal can flow therethrough. If a brake shoe is to be constructed in which the lug is formed as part of the casting, the part 52 of the lining will be provided on its upper and lower sides with slots, as shown in Fig. 2^a and the jaws 39^a will be provided each with only a single finger or tooth which projects through the slots into engagement with each other to form the eyelet or perforation of the cast lug. In either event it will be noted that the jaws serve to insure that the brake shoe will be moved outwardly with the mold sections 15 so that the cast shoes will be discharged when the mold arrives to the position shown in Fig. 3 when the jaws open and release the casting.

Preferably at a point slightly in advance of line 3-3 in Fig. 10, that is to say, at the point where the movable mold section is being inverted to automatically discharge the casting, the cam track 32 is bent sharply away from the mold and the cam track 25 is bent sharply inwardly toward the swinging arms or supports 20, so that the mold sections 15 will be quickly shifted and will strike with a sharp blow against the cam track 32 to jar the castings loose and insure their discharge from the molds.

The vents for the mold cavities cannot extend upwardly, as usual at the parting line of the mold sections, since the continuous trough extending over all the closed molds is provided at this point in order to insure the filling of several molds at once and in order that the excess metal from one mold may flow on to the next succeeding molds. In order to provide for proper ventage the sheet metal lining 50 is somewhat less in width than the mold section 15 so that vertical passages 56 (see Fig. 8) are provided between the edges of the liner and the radial supports or plates 16. These passages (see Fig. 7) extend downwardly from a point adjacent the top of the mold cavity but cannot be extended upwardly therefrom, for in that event they would prevent the formation of the continuous pouring trough 46 extending over the closed molds. These passages thus open to the air at the bottom of the mold sections.

Wide and shallow vent grooves 57 (see Figs. 2 and 7) are formed in the surface of the liner and connect the upper portion of the mold cavity with the vertical passages 56. As the 5 mold fills, the air and gases formed escape through these shallow grooves or vents 57 and down through the passages 56. The grooves, as stated, are at the top of the mold cavity and are so shallow that they chill the 10 iron when it reaches and enters them, thereby avoiding any material flow of the molten metal through the vent or vents to the exterior. If desired or necessary, half-round 15 grooves or vents 58 (see Figs. 5 and 7) may be formed in the sides of the mold section 15 and which extend horizontally from the back of the mold section to the upper ends of the 20 passages 56. When the vent openings or grooves 58 are employed the lower ends of the vent passages 56 may be closed.

The casting of metal articles in metallic molds causes the articles to be more or less chilled in accordance with the properties of the metal employed. In some instances it is 25 preferable that the cast iron should be chilled as little as possible, as for instance, in the larger portion of the working face of a brake shoe. To avoid such chilling the mold section 14, which forms the wearing face of the 30 shoe, is provided with inserts 59 (see Figs. 2, 6 and 8) of non-chilling material, such as graphite or clay, or a mixture of the two. These inserts are preferably held in place 35 against displacement by a plate 60 of sheet iron or steel, set into a recess in the back of the mold section 14. This plate, when the mold is in position (see Fig. 8), abuts against the flanges 17 of the radial supports or plates 16 and is securely held in place. Where the 40 molten metal comes in contact with these inserts it is very much less chilled than where it comes in contact with the iron surfaces of the mold. By a suitable arrangement of the 45 non-chilling inserts 59, such for example as shown in Fig. 6, a brake shoe is made which will present a wearing face made up of chilled and non-chilled portions.

It should be noted that the pouring trough 50 formed between the upper sections of the molds, gates 49 and the vents 56, 57 and 58 are all formed at parting lines of the mold sections so that they open and close with the sections and rapidly clear themselves of molten metal. In this way they will not become clogged by chilled metal and, if they do, can be readily cleared. It should be further noted that the movable mold sections 55 open outwardly or away from the center of the movable frame or carrier, so that the upper portions of the movable mold sections may be arranged to abut to form the pouring trough 46 when the sections of the mold are closed. If the movable mold sections opened inwardly they could not be provided with portions arranged to abut when

in closed position. Moreover it should be noted that in the open position of the mold sections the working faces of the molds are exposed and ready access afforded thereto for cleaning and the like. The molds are 70 automatically and successively closed to complete the mold cavities and form the castings when they are opened and inverted to automatically discharge the castings.

It is obvious that while the machine is 75 shown as particularly designed for the manufacture of brake shoes, that it may be employed for casting other articles and that numerous modifications may be made in the details set forth without departure from the 80 essentials of the invention.

Having described my invention, what I claim as new and desire to secure by Letters Patent, is:

1. An automatic, continuously operating 85 casting apparatus comprising a series of traveling molds, each mold consisting of separable sections, mechanism for automatically moving one of the sections of each mold to and from the other in a curved path at an 90 angle to the plane of movement of the molds to open and close the same, and means for continuously supplying molten metal to the closed molds.

2. An automatic, continuously operating 95 casting apparatus comprising a series of traveling molds, each mold consisting of separable sections, mechanism for automatically and successively moving one of the sections of each mold to and from the other to 100 open and close the same and for inverting the movable mold section in open position to discharge the casting, and means for continuously supplying molten metal to the closed molds.

3. A continuously operating, automatic 105 casting apparatus comprising a traveling carrier and a series of molds mounted thereon, each mold consisting of a fixed and a movable mold section, said movable mold 110 sections being independently shiftable in curved paths to and from the fixed mold sections and at an angle to the plane of movement of said carrier, mechanism for controlling the shift of said movable mold sections to automatically open and close the molds 115 and means for continuously supplying molten metal to the closed molds.

4. A continuously operating automatic 120 casting apparatus comprising a rotating mold carrier, a plurality of molds mounted thereon, each mold having a movable section, mechanism for shifting the movable mold sections to and from the other sections to automatically close and open the molds 125 and for revolving the movable sections when in open position to automatically discharge the casting, and means for continuously supplying molten metal to the closed molds.

5. An automatic casting apparatus com- 130

prising a series of traveling molds, each having a movable mold section and a series of pivoted arms whereon said movable mold sections are mounted to shift bodily in curved paths to and from open position and mechanism for continuously and automatically controlling the operation of the movable mold sections.

6. A continuously operating automatic casting apparatus comprising a traveling carrier, a plurality of molds mounted thereon, each mold having a movable section, a series of pivoted supports whereon said movable mold sections are mounted, mechanism controlling the shift of said supports to automatically open and close the molds, and means for continuously supplying molten metal to the closed molds.

7. A casting apparatus comprising a rotating frame and a series of molds mounted thereon, each mold having a section movable to and from open position, a cam and lever mechanism for shifting said movable mold sections and for partially rotating the same in open position to discharge the castings.

8. A casting apparatus comprising a rotating frame and a plurality of molds mounted thereon, each of said molds having a section movable to and from open position, a series of pivoted levers whereon said movable mold sections are mounted and a cam track controlling the movement of said levers.

9. A casting apparatus comprising a series of traveling molds having sections movable to and from open position, a shiftable support for each of said mold sections, said sections being shiftably mounted on said supports, means for controlling the movement of said supports and means for controlling the movement of said mold sections thereon.

10. A casting apparatus comprising a traveling carrier and a series of molds mounted thereon having mold sections shiftable to and from closed position, a series of pivoted supports whereon said movable mold sections are rotatably mounted and cam tracks controlling the movement of said supports and said movable mold sections.

11. An automatic casting apparatus comprising a rotatable frame, a series of molds mounted thereon, each of said molds consisting of separable sections, one of which is movable to and from the other, a series of arms pivoted on said frame, said movable mold sections being movably mounted upon said arms to move revolubly to and from the other sections and mechanism controlling the movement of said arms and said movable mold sections to automatically and successively open and close the molds.

12. A casting apparatus comprising a series of traveling molds having shiftable sections and a pair of pivoted arms for each mold whereon the shiftable mold section is movably mounted to shift to and from open

position and to be partially revolved or rotated when in open position.

13. A casting apparatus comprising a rotating frame, a plurality of molds mounted thereon having mold sections movable to and from open position, a pair of pivoted supports for each mold to which the movable mold section is pivotally connected and mechanism controlling the movement of said supports whereby said movable mold sections are automatically moved to and from closed position and partially rotated when in open position to automatically discharge the castings.

14. A casting apparatus comprising a rotating frame or carrier and a plurality of molds mounted thereon having sections movable to and from open position, a pair of pivotal supports whereon each of said mold sections is pivotally mounted and cam tracks controlling the movement of said supports and movable mold sections.

15. In a continuously operating, automatic casting apparatus, the combination with a traveling mold carrier, of a series of molds, each comprising a fixed and a movable mold section, mechanism for automatically shifting the movable mold sections to and from open position, and for partially revolving the same when in open position and means for continuously supplying molten metal to the closed molds.

16. A continuously operating, automatic casting apparatus comprising a movable mold carrier, a plurality of molds mounted thereon, one of the sections of each mold being pivotally supported with respect to its companion section, mechanism for automatically and successively shifting said pivoted mold section to open and close the molds and means for continuously supplying molten metal to the closed molds.

17. A continuously operating, automatic casting apparatus comprising a rotating carrier provided with a plurality of mold sections, mechanism for automatically and successively opening and closing said mold sections and for turning one of the sections of each mold with respect to its companion section to automatically discharge the casting, and means for continuously supplying molten metal to the closed molds.

18. A casting apparatus comprising a rotating mold carrier and a plurality of fixed and movable mold sections on the periphery of said carrier, a pair of swinging supports for each movable mold section, each movable mold section being pivoted to the corresponding pair of swinging supports, and means controlling the movement of said supports and of said movable mold sections to automatically open and close the molds.

19. A casting apparatus comprising a carrier traveling in a horizontal plane and a series of molds mounted thereon, each hav-

- ing sections movable to and from closed position, a plurality of swinging counter-weighted supports wherein said movable sections are pivoted, means for controlling the movement of said supports and means for controlling the movement of the mold sections thereon.
20. A casting apparatus comprising a traveling carrier provided with fixed and movable mold sections, pivoted arms for sustaining said movable mold sections and a cam shaped rail controlling the movement of said arms and said mold sections.
21. A casting apparatus comprising a traveling mold carrier provided with fixed and movable mold sections, pivoted arms for sustaining said movable mold sections, a cam shaped rail for engaging and shifting said arms and a second cam shaped rail for engaging and shifting said movable mold sections.
22. A casting apparatus comprising a traveling carrier, a series of molds independently and removably mounted on said carrier, each of said molds having a section movable to and from open position and means for automatically shifting said movable mold sections.
23. A casting apparatus comprising a traveling carrier and a plurality of molds, said molds and carrier having interlocking projections and lugs whereby said molds are independently and removably sustained in position upon said carrier and means for automatically opening and closing said molds.
24. A casting apparatus comprising a rotating frame, a series of molds independently and removably mounted on said frame, each of said molds comprising a relatively fixed and a movable section, swinging supports connecting the sections of each of said molds and means for automatically controlling the movement of each of said supports to open and close the molds.
25. An automatic, continuously operating casting apparatus comprising a number of molds arranged in endless series, each of said molds consisting of relatively movable mold sections, one at least of the sections of each mold being mounted to revolve to and from the other section thereof, whereby ready access is afforded to the working faces of the mold sections when in open position, mechanism arranged to automatically and successively shift said mold sections to open and close the molds, and means for continuously conducting molten metal to the closed molds, substantially as described.
26. An automatic continuously operating casting apparatus comprising a number of molds arranged in circular series, each of said molds consisting of relatively fixed and movable sections, mechanism arranged to automatically and successively shift said movable mold sections to and from open position and for inverting the same in open position to automatically discharge the casting, and means for continuously conducting molten metal to the closed molds, substantially as described.
27. An automatic casting apparatus comprising a number of molds arranged in circular series, each of said molds consisting of relatively fixed and movable sections, a series of pivoted supports whereon said movable mold sections are movably mounted and means controlling the shift of said supports and the movement of the mold sections thereon and arranged to automatically open and close the molds and invert the movable mold sections when in open position, substantially as described.
28. A continuously operating, automatic casting apparatus comprising a number of molds, each consisting of relatively movable sections and all traveling in an endless circuit, one of the sections of each mold being arranged to revolve to and from the other to expose the working surfaces of said mold sections in open position, mechanism arranged to automatically and successively open and close said molds at different parts of the circuit and means for continuously supplying molten metal to the closed molds substantially as described.
29. A casting apparatus comprising a series of molds, each having a movable section and all arranged to travel in an endless circuit, a series of swinging supports whereon said movable mold sections are mounted to swing in curved paths to and from open position and mechanism for automatically shifting said movable mold sections to open and close the molds at different parts of the circuit, substantially as described.
30. A casting apparatus comprising a series of molds arranged in a substantially horizontal plane and traveling in an endless circuit, each of said molds consisting of relatively fixed and movable mold sections abutting along a substantially vertical parting line and mechanism arranged to automatically and successively shift said movable mold sections to and from open position and for inverting the same in open position, substantially as described.
31. A casting apparatus comprising a series of molds arranged to travel in an endless circuit and each having a movable mold section, of a series of swinging arms whereon said movable sections are pivoted, mechanism controlling the movement of said arms and movable mold sections to automatically open and close the molds and invert the movable mold sections when in open position, substantially as described.
32. A casting apparatus comprising a series of molds arranged to travel in an endless circuit and each having a relatively fixed and a movable mold section, a series of swinging arms arranged in pairs, each movable mold

- section being pivotally connected to a pair of said arms and mechanism controlling the movement of said arms to automatically open and close the molds and invert said 5 movable mold sections when in open position, substantially as described.
33. A casting apparatus comprising a series of molds arranged in a substantially horizontal plane and traveling in an endless circuit, said molds comprising inner fixed sections and outer movable sections abutting along a substantially vertical parting line, a series of radially swinging supports whereon said outer movable mold sections are mounted and mechanism controlling the movement of said supports and movable mold sections to automatically and successively open and close the molds at different parts of the circuit, substantially as described.
34. A casting apparatus comprising a carrier, a series of molds independently and removably mounted on said carrier, each of said molds comprising connected relatively movable sections and mechanism arranged to automatically shift said sections to open and close the molds, substantially as described.
35. A casting apparatus comprising a mold carrier movable in a substantially horizontal plane, a series of molds mounted thereon each consisting of relatively fixed and movable mold sections, a series of swinging supports whereon said movable mold sections are pivoted and mechanism controlling the movement of said supports and said movable mold sections to automatically open and close the molds and partially rotate said movable mold sections when in open position to automatically discharge the castings, substantially as described.
36. A casting apparatus comprising a suitable frame or carrier, a series of relatively fixed mold sections movably and independently mounted upon said frame or carrier, a series of swinging supports pivotally mounted on said fixed mold sections, a series of movable mold sections mounted on said supports and means for automatically and successively shifting said movable mold sections 50 to open and close the mold, substantially as described.
37. A casting apparatus comprising a rotatable frame, a series of relatively fixed mold sections independently and movably mounted on said frame, a pair of swinging supports carried by each of said mold sections, movable mold sections pivotally connected to each pair of said supports and means for automatically shifting said movable mold sections to open and close the molds, substantially as described.
38. A casting apparatus comprising a horizontal rotating carrier and having a series of radial supports, a series of molds sustained 65 between said supports, said molds and supports having vertically disposed interlocking grooves and ribs and said molds having parts overlapping the upper edges of said supports.
39. A casting apparatus comprising a traveling frame and a series of molds on said frame consisting of separable sections, means for opening and closing the movable mold sections at different parts of the circuit, pouring gates at the parting line of the mold sections, said mold sections having portions forming a pouring trough when in closed position that extends parallel to the parting line of the mold and continuously from mold to mold.
40. A casting apparatus comprising a rotating frame and a series of molds mounted thereon, each of said molds comprising a fixed and a movable mold section and means for shifting said movable mold sections to and from said fixed mold sections at different parts of the circuit, said molds having a pouring trough traveling therewith and gates at the parting lines of said molds to which the metal is conducted by said trough.
41. A casting apparatus comprising a traveling frame, a series of molds mounted on said frame to move in continuous circuit, each of said molds consisting of separable sections, means for opening and closing said sections at different parts of the circuit, said molds 95 having pouring gates at the parting line of the mold sections and said molds also having a trough extending continuously between two or more of said gates to conduct the molten metal thereto when said mold sections are in closed position.
42. A casting apparatus comprising a horizontal rotating frame, a series of molds mounted thereon to travel in a continuous circuit, each of said molds comprising separable sections, means for opening and closing said mold sections at different parts of the circuit, said molds having pouring gates at the parting lines of said sections and having portions arranged to form a continuous 100 trough communicating with two or more of said gates when said mold sections are in closed position.
43. A casting apparatus comprising a series of permanent molds, each having separable sections arranged to be closed together to receive the molten metal and to be opened to discharge the castings, a holding device for supporting inserts or the like in the mold cavity and means for releasing said holder 115 when the mold is open.
44. A casting apparatus comprising a series of molds having separable sections, means for automatically opening and closing said mold sections, a holder for supporting 125 inserts or the like in a mold cavity and means for shifting said holder to release the inserts when said mold sections are open.
45. A casting apparatus comprising a traveling frame, a series of molds comprising sepa-

5
rable sections mounted on said frame, means for automatically opening and closing said sections, a shiftable finger coöperating with one of said mold sections and means for moving said finger as the sections are opened and closed.

10
46. A casting apparatus comprising a traveling frame, a series of molds mounted on said frame, each comprising a fixed and a movable section, said movable mold section being mounted to swing on a pair of pivoted supports, means for controlling the movement of said supports to open and close the mold sections, a shiftable finger carried by 15
said movable mold section and means controlled by the movement of said supports for shifting said finger.

20
47. A casting apparatus comprising a traveling frame, a series of molds mounted on said frame, each comprising a fixed and a movable section, said movable mold section being mounted to swing on a pair of pivoted supports, means for controlling the movement of said supports to open and close the 25
mold sections, a pair of shiftable fingers or jaws mounted on said movable mold section and means controlled by the movement of said supports for opening and closing said fingers or jaws.

30
48. A casting apparatus comprising a series of molds consisting of separable sections all traveling together in an endless circuit, means for shifting said mold sections to open and close the molds, the separate sections 35
of the several molds having portions arranged to form a pouring trough when said mold sections are in closed position that extends continuously from mold to mold, and said molds having gates leading from said trough to the 40
mold cavities, substantially as described.

45
49. A casting apparatus comprising a series of molds each consisting of relatively fixed and movable mold sections and all arranged to travel in an endless circuit, mechanism for automatically opening and closing said movable mold sections at different parts of the circuit, said fixed and movable mold sections having portions forming a pouring trough when said mold sections are in closed 50
position that extends continuously between two or more of said molds, substantially as described.

55
50. A casting apparatus comprising a series of molds consisting of relatively fixed and movable mold sections all arranged to travel in an endless circuit, said fixed and movable mold sections having portions forming, in closed position, a pouring trough on opposite sides of the parting line between 60
said fixed and movable mold sections and above the mold cavities and that extends continuously between two or more of said molds, and gates at the parting lines between said fixed and movable mold sections leading

from said trough to the mold cavities, substantially as described. 65

51. A casting apparatus comprising a series of molds each formed of relatively fixed and movable mold sections, said mold sections having portions abutting in closed position and arranged to form a trough extending continuously between two or more of said molds, and said mold sections having gates leading from said trough to the mold cavities and mechanism for automatically shifting said movable mold sections to open and close the molds at different parts of the 70
circuit, substantially as described.

52. A casting apparatus comprising a series of molds each formed of relatively fixed and movable mold sections and arranged to travel in an endless circuit, said movable mold sections being shiftable outwardly in radial direction to open position and having portions abutting in closed position to form 85
a continuous trough extending between the closed molds and means for automatically shifting said movable mold sections to open and close the molds, substantially as described. 90

53. A casting apparatus comprising a series of molds formed of inner fixed and outer movable mold sections and all arranged to travel in an endless circuit, means for automatically shifting said movable mold sections outwardly to open position and for inverting the same in open position, said fixed and movable mold sections having portions forming a continuous trough in closed position which extends between two or more of 100
said molds and gates at the parting lines of said fixed and movable mold sections leading from said trough to said mold cavity, substantially as described.

54. A continuously operating, automatic 105 casting apparatus comprising a series of relatively fixed and movable mold sections, all traveling together in an endless circuit, mechanism arranged to automatically and successively shift said movable mold sections to open and close the molds, said molds having vents in the parting lines between the fixed and movable sections thereof leading from the upper portions of said mold cavities and means for continuously supplying molten metal to the closed molds, substantially 110
as described.

55. A continuously operating, automatic casting apparatus comprising a series of molds arranged in a substantially horizontal 120
plane, each of said molds comprising relatively fixed and movable mold sections, mechanism arranged to automatically shift said movable mold sections to open position and to invert the same in open position said 125
molds having vents and gates formed in the parting lines between the relatively fixed and movable mold sections of the several

molds and means for continuously supplying molten metal to the closed molds, substantially as described.

56. A casting apparatus comprising a series of molds arranged in a substantially horizontal plane and each consisting of inner fixed and outer movable mold sections abutting in a substantially vertical parting line, a series of swinging supports whereon said 10 movable mold sections are mounted, means for automatically shifting said supports to move said movable mold sections to open position and for inverting the same when in open position and a series of vents and gates 15 formed in the parting lines between the fixed and movable mold sections, substantially as described.

57. A casting apparatus comprising a series of molds arranged in a plane slightly inclined to the horizontal, each of said molds 20 consisting of inner fixed and outer movable mold sections and all arranged to travel together in an endless circuit, mechanism for shifting said movable mold sections to automatically open and close the molds at different parts of the circuit, said mold sections having portions abutting in closed position to form a trough extending continuously between two or more of said molds, and gates 25 30 in the parting lines between said fixed and movable mold sections leading from said trough to the mold cavities, substantially as described.

58. A casting apparatus comprising a series of molds arranged in a substantially horizontal plane, each of said molds consisting of an inner fixed and an outer movable mold section, a series of pivoted arms whereon said movable mold sections are pivotally 35 40 mounted, mechanism for automatically shifting said arms to open said molds and means for inverting said movable mold sections when in open position, said fixed and movable mold sections having portions abutting 45 in closed position and arranged to form a trough extending continuously between two or more of said molds, and said mold sections having gates at the parting lines between said fixed and movable mold sections leading 50 from said trough to the mold cavities.

59. A continuously operating, automatic casting apparatus comprising a series of molds, each consisting of relatively fixed and movable mold sections, gates and vents 55 formed in the parting lines between said fixed and movable mold sections, said mold sections being arranged to travel together in endless series, mechanism arranged to automatically and successively shift said mold 60 sections to open position and to partially revolve the same when in open position, whereby free access is afforded to said gates and vents for clearing and the like, substantially as described.

65. 60. A casting apparatus comprising a

number of molds arranged in a substantially horizontal plane, each of said molds consisting of inner fixed and outer movable mold sections abutting on a substantially vertical parting line and all traveling in an endless circuit, means for automatically shifting said movable mold sections at different parts of the circuit to open and close the molds, said fixed and movable mold sections having portions abutting in closed position to form a trough 70 extending above the mold cavities and continuously between two or more of said molds, gates at the parting lines of said fixed and movable mold sections leading from said trough to the mold cavities and downwardly extending vents at the parting lines of said fixed and movable mold sections leading from the upper portions of said mold cavities, substantially as described.

61. A casting apparatus comprising a rotating frame revoluble in a substantially horizontal plane, a series of molds mounted on said frame, each consisting of inner fixed and outer movable mold sections abutting on a substantially vertical parting line, said mold sections having portions abutting in closed position to form a trough extending above the mold cavities and continuously between two or more of said molds, said molds having gates at the parting lines of said fixed and movable mold sections leading from said trough to the mold cavities and having also downwardly opening vents at the parting lines between the fixed and movable mold sections leading from the upper portions of the mold cavities and means for automatically shifting said movable mold sections to open position and for inverting the same when in open position to expose the working faces, gates and vents of the molds, substantially as described.

62. A casting apparatus comprising a frame rotatable in a plane slightly inclined to the horizontal, a series of molds mounted thereon, each consisting of an inner fixed and an outer movable mold section, mechanism for automatically opening and closing said movable mold sections, said mold sections having portions forming a trough in closed position that extends continuously between two or more of said molds and said molds having gates leading from said trough to the mold cavities, substantially as described.

63. A casting apparatus comprising permanent mold sections, one of which is formed of metal and provided with non-metallic inserts forming part of the surface of the mold cavity.

64. A casting apparatus comprising permanent separable mold sections, one of said sections having a removable working face or lining formed of relatively thin sheet metal having a high fusion point.

65. A casting apparatus comprising a plurality of traveling molds, each formed of

separable sections, means for automatically opening and closing said mold sections and latches for holding said mold sections in closed position.

5 66. A casting apparatus comprising a plurality of traveling molds, each formed of separable sections, means for automatically opening and closing said mold sections, latches for holding said mold sections in closed position and means for automatically tripping said latches.

10 67. A casting apparatus comprising a rotating carrier provided with a plurality of

radial mold supports, fixed mold sections movably mounted between said supports, 15 movable mold sections co-operating with said fixed mold sections, means for supporting and shifting said movable mold sections and latch bars projecting from the mold carrier and engaging the movable mold sections 20 when in closed position.
